SHUTTER HOLDER

Filed March 4, 1930

Inventor

John O. Wesner.

By Clarence A. O'Brien.
Attorney

UNITED STATES PATENT OFFICE

JOHN O. WESNER, OF STEWART MANOR, NEW YORK

SHUTTER HOLDER

Application filed March 4, 1930. Serial No. 433,091

This invention relates to new and useful improvements in shutter holders and has for one of its important objects to provide, in a manner as hereinafter set forth, a device 5 of this character embodying novel means adapting the same for use in holding shutters of different thicknesses in a manner to prevent rattling or movement of said shutters.

Another important object of the invention 10 is to provide a shutter holder adapted to secure a shutter in open position against the swinging movement and embodying a pivotally mounted gravity actuated latch member adapted for engagement with the shutter to 15 releasably retain the same.

Other objects of the invention are to provide, in a manner as hereinafter set forth, a shutter holder of the character described which will be extremely simple in construction, strong, durable, efficient in its use and 20 which may be manufactured at low cost.

All of the foregoing and still further objects and advantages of the invention may 25 become apparent from a study of the following specification, taken in connection with the accompanying drawings wherein like characters of reference designate corresponding parts throughout the several views, and wherein:—

30 Figure 1 is a view principally in longitudinal section showing a shutter holder constructed in accordance with this invention mounted in operative position.

35 Figure 2 is a perspective view of the device.

Referring to the drawings in detail, it will 40 be seen that the reference numeral 1 designates a flat, horizontally disposed metallic bracket having an integral right angularly disposed upturned extension 2 provided with 45 openings 3 for the passage of the securing screws 4 for rigidly mounting the bracket 1 on the wall 5.

Intermediate its ends, the bracket 1 is provided with a struck-up bendable tongue 6 adapted to be engaged by the lower end portion of the shutter 7, said tongue constituting a stop for the shutter.

As clearly indicated in dotted lines in Figure 50 1 of the drawing, the tongue is adapted

to be bent to various positions to accommodate shutters of different widths.

The bracket 1 terminates in a down turned end portion 8 to which is swingingly secured for movement in a vertical plane through the 55 medium of the pivot bolts 9 a gravity actuated latch member 10 having an integral extension handle 11 thereon of greater length and width than the latch member 10 and adapted to normally maintain said latch 60 member in raised operative position, as seen in the drawing. The latch member 10 is adapted for engagement with the opposite side of the shutter 7 from the stop tongue 6.

In use, the latch member 10 is manually 65 swung out of the path of the shutter 7 when it is desired to release or secure said shutter in open position. The greater length and width of the handle extension 11 will retain the latch member in operative position and 70 the curved upper end portion of said latch member facilitates the swinging movement thereof across the face of the shutter. The bendable tongue 6 may be adapted to shutters of different thicknesses and said shutter will thus be retained against vibration or 75 rattling between the tongue and the latch member 10.

It is believed that the many advantages of a shutter holder constructed in accordance 80 with this invention will be readily understood, and although the preferred embodiment of the invention is as illustrated and described, it is to be understood that changes 85 in the details of construction may be had which will fall within the scope of the invention as claimed.

What is claimed is:—

1. A shutter holder of the character described comprising a bracket, an integral 90 bendable tongue extending from the bracket, and a latch member pivotally mounted for swinging movement on the bracket and engageable with a shutter in a manner to retain the same between the tongue and said latch member.

2. A shutter holder of the character described comprising a horizontally disposed bracket, an integral, bendable tongue extending 95 upwardly from the bracket for engage-

ment with the shutter and a latch member mounted for swinging movement on the bracket in spaced relation to the tongue and engageable with a shutter in a manner to retain the same between the tongue and said latch member.

5 3. A shutter holder of the character described comprising a horizontally disposed bracket, means for securing the bracket on a support, an integral bendable tongue struck up from an intermediate portion of the bracket for engagement by the shutter, said tongue constituting a stop for the shutter and a gravity actuated latch member mounted for 10 swinging movement on the bracket for engagement with a shutter in a manner to retain the same between the tongue and said latch member.

15 4. A shutter holder of the character described comprising a horizontally disposed, flat, metallic bracket having an integral up-turned portion on one end constituting means for securing said bracket on a support, and a down turned, integral extension on the opposite end, a transversely extending, integral bendable tongue struck up from an intermediate portion of the bracket for engagement by the shutter and constituting a stop therefor and a gravity actuated latch member mounted 20 for swinging movement on the extension for engagement with a shutter in a manner to retain the same between the tongue and said latch member.

30 In testimony whereof I affix my signature.
35 JOHN O. WESNER.
